UNITED STATES PATENT OFFICE.

EDWARD Y. MOORE, OF CLEVELAND, OHIO.

TROLLEY-HOIST.

1,122,295.

Specification of Letters Patent. Patented Dec. 29, 1914.

Application filed May 19, 1910. Serial No. 562,123.

To all whom it may concern:

Be it known that I, EDWARD Y. MOORE, a citizen of the United States, residing at Cleveland, in the county of Cuyahoga and 5 State of Ohio, have invented a certain new and useful Improvement in Trolley-Hoists, of which the following is a full, clear, and exact description, reference being had to the accompanying drawings.

10 The primary object of this invention is to provide a trolley or trolley hoist adapted to run on a trackway and having the capacity to swing the load support to either side of the trackway.

15 The mechanism has many uses where it is desired to convey a load and support it in a position which may not be exactly under the trackway.

20 My mechanism may well be embodied with raising mechanism, thereby constituting a trolley hoist.

25 The invention includes not only means for swinging the load support to either side of the trackway, but also means for locking it in any swung position, and means for clamping the trolley to the track.

30 The supporting of the hoisting mechanism at two points, one being swivel and the other a traveling roller, is also one of the features of this invention.

Other features are also included, which will be hereinafter more fully explained.

35 The drawings illustrate my invention as embodied in the trolley hoist. Figure 1 is a side elevation of such mechanism; Fig. 2 is a front or end elevation; Fig. 3 is a vertical central section on a plane parallel with Fig. 1; Fig. 4 is a sectional plan, the section plane being located just below the track, 40 as indicated by the line 4-4 of Fig. 1; Fig. 5 is a horizontal section in a plane just above the traveling supporting roller, as indicated by the line 5-5 of Fig. 3, the arcual track for the roller being omitted 45 for clearness of illustration.

The supporting track shown comprises a usual I-beam having a web 10 and projecting flanges 11. Riding on the flanges of the I-beam are the trolley wheels 15, which are 50 shown as mounted on studs 16 projecting from brackets 17, of an inverted U-shape. These brackets are secured near their lower ends to the trolley frame 20 by means of rods 21, which extend through the brackets 55 and through ears 22 on the trolley frame. Rigidity between the brackets and trolley

frame is provided by cap-screws 23, screwing through the projecting portions 24 of the brackets into the trolley frame. The rods 21 may be prevented from displacement 60 by pins 25 driven through them. The described construction is a very strong and effective one for connecting the supporting wheels with the trolley frame, and, at the same time, allows the parts to be easily assembled and disassembled. The driving out 65 of the pins 25 allows the rods 21 to be driven out of the ears and the removal of the cap-screws 23 completes the separation. By reason of the U-shape of the brackets upon 70 which the supporting wheels are mounted, the trolley may easily pass around curves or through switches, as shown, described and claimed in my prior application #547,001. This ease of passage is enhanced by having 75 the legs of the brackets 17 elliptical in cross section, as shown in Fig. 4.

As shown more particularly in Fig. 3, on the under side of the trolley frame 20 is a downwardly extending boss 30, in which is rigidly mounted a vertical stud 31. Surrounding this stud is a sleeve 32, from which extends a projecting portion 33, which forms a part of the frame of the hoist mechanism, or other load support, as hereinafter explained. In the bore of the sleeve, and bearing on the stud 31, are bushings 35 and 36, and below the sleeve and the bushing 36 is a washer 37, and below this washer is a nut 38 screwing onto the lower end of 80 the stud and pinned to it. The sleeve and frame member 33 is thus swiveled on the stud. 85

Rising from the swinging frame 33 is an ear 39, in which is mounted a stud 40, on 90 which is a roller 42. This roller bears on an arcual track 43, provided by the segmental flange extending inwardly from the lower edge of the front vertical wall 44 of the frame 20. The load is supported by suitable 95 mechanism mounted in plates 50 and 51, which are secured by bolts 52 to the swiveled member 33. Accordingly, it results that the load is supported at two points; namely, by the swiveling stud and the roller 42, and this 100 eliminates lateral strains in the swivel. When the sleeve 32 is turned on the stud 31, the wheel 42 travels on the flange 43, and the load supporting mechanism is accordingly 105 shifted to one side or the other of the track-way. 110

The carrying of the load to either side of

the track, by reason of the swivel and roller support, is one of the important features of this invention. When the load is so carried to one side or the other, it tends to tip the mechanism downwardly on the loaded side. This is resisted by lugs 55, on the brackets 17, on the opposite side from the load, engaging the under side of the trackway. These lugs, accordingly, not only prevent 10 material tipping of the mechanism, but automatically lock it in position when the load is at one side or the other of the center. Though the load may travel a considerable distance to either side, it will be noted that 15 it never passes out of the space between the transverse planes through the centers of the supporting wheels, so that there is never any tendency to tip the mechanism endwise.

To conveniently swing the swiveled frame 20 on the stud and lock it in any desired position, I provide a worm-wheel 60, which is keyed to the sleeve 32 and meshes with a worm 61, on a shaft 62, which has a hand-chain-wheel 63. Accordingly, the rotation 25 of this hand-chain-wheel swings the hoisting mechanism, or load supporting mechanism, to either side of the track, as desired, and automatically locks it wherever it is left. The shaft 62 of the worm is journaled in the 30 bosses 65 and 66, extending downwardly from the upper portion of the frame 20, and provided with suitable caps 67 on their under sides, secured by cap-screws 68. The range of movement of the swiveled structure is 35 limited by the stop-screws 57, screwing downwardly through the frame 20 into position to stand in the path of the ear 39, which carries the stud for the roller 42.

The mechanism for supporting the load 40 carried by the plates 50 and 51 may be of any form desired, either a simple supporting mechanism or a hoisting mechanism. The latter is the form shown herein, and may be briefly described as consisting of a drum 70 45 mounted on a stationary sleeve 71 and having a gear 72 which meshes with a pinion 73 on the shaft 74, which shaft, in turn, carries a gear 75 meshing with a driving pinion 76. This latter pinion is on the end of a shaft 77, 50 which passes through, and loosely occupies, the sleeve 71, and, at its other end, carries a hand wheel 78, whereby it may be rotated. The connection between the hand wheel and shaft may, if desired, be of a ratchet and 55 brake nature, as illustrated in my Patent

#797,997, whereby the hoisting mechanism is self-locking, but the load may be lowered, by keeping the hand wheel ahead of the position given the shaft 77 by the descending load.

60

Having thus described my invention, what I claim is:—

1. The combination of a depending trolley frame, supporting wheels carried thereby, a load supporting member, a swivel connection 65 between the same and the trolley frame adapted to partially support the load, a trackway on the trolley frame and a roller on the load supporting member, whereby the load may be swung to either side of the 70 track, means for confining the range of such movement to the space between transverse planes through the axes of the supporting wheels, and hoisting mechanism carried by said member between the swivel and roller. 75

2. The combination, with a trolley frame and supporting wheels, of a bracket for carrying one of the wheels, a rod for pinning said bracket to the frame, and a screw passing through an extension of the bracket into 80 the frame.

3. The combination, with a frame, of a U-shaped bracket, a pair of supporting wheels carried thereby, a rod extending through the legs of the bracket and through 85 ears on the frame, and additional means for securing two legs of the bracket to the trolley frame.

4. The combination, with a frame, of a U-shaped bracket, a pair of wheels carried 90 thereby, a rod extending through the legs of the bracket and through ears on the frame, and lugs projecting inwardly from the legs of the bracket and adapted to stand beneath the flange of an I-beam on which the wheels 95 ride.

5. The combination of a wheeled trolley frame, a horizontal arm pivotally mounted on the trolley frame and adapted to swing in a horizontal plane, a roller and trackway, 100 one of which is carried by the arm and the other by the frame, a hoist carried by the arm, and self-locking mechanism for swinging the arm in either direction.

In testimony whereof, I hereunto affix my 105 signature in the presence of two witnesses.

EDWARD Y. MOORE.
